US00D685374S

(12) **United States Design Patent**
Schindler

(10) **Patent No.:** US D685,374 S
(45) **Date of Patent:** ** Jul. 2, 2013

(54) **SMART-KEY**

(75) Inventor: **Dominic Schindler**, Lauterach (AT)

(73) Assignee: **Deckel Maho Pfronten GmbH**,
Pfronten (DE)

(**) Term: **14 Years**

(21) Appl. No.: **29/386,216**

(22) Filed: **Feb. 25, 2011**

Related U.S. Application Data

(62) Division of application No. 29/309,959, filed on Nov. 19, 2008, now Pat. No. Des. 645,866.
